Application December 29, 1949, Serial No. 135,784

7 Claims. (Cl. 202—56)

1

This invention relates to an improved method for purifying synthetic alcohols and, more specifically, to a method for purifying higher boiling alcohols derived from the Oxo process and which contain impurities of the type tending to undergo decomposition at the normal atmospheric boiling point of the alcohol.

Co-pending application Serial No. 136,295 describes a method for purifying the synthetic Oxo alcohols by conducting the distillation in a manner such that a significant proportion of the alcohols are left as a bottoms fraction during the alcohol distillation. Co-pending application Serial No. 136,281 utilizes a sub-atmospheric distillation process for the purification of the synthetic Oxo alcohols in the prevention of degradation of high boiling impurities.

An improved distillation process for impure alcohols obtained by the Oxo process has been discovered whereby the alcohol is distilled in the presence of an intermediate boiling fraction having a boiling range of from 20 to 100 degrees Fahrenheit above that of the alcohol, thereby maintaining the liquid temperature below the critical point.

In order to avoid the high bottoms temperatures which normally exist in a column during distillation of the Oxo alcohols, it has been found advantageous to have present in the distillation zone during the alcohol distillation a material such as an alcohol or hydrocarbon having a somewhat higher boiling range than the alcohol undergoing distillation. This material can be added directly to the alcohol feed to the distillation zone or it can be a higher boiling alcohol formed during the Oxo process which is used to produce the alcohol desired. In either case, the effect on the distillation is to have a bottoms fraction composed largely of the higher boiling alcohol or hydrocarbon, thus permitting maximum recovery of the desired Oxo alcohol.

Many alcohols which are of great commercial importance are prepared by synthetic processes and especially by the so-called Oxo reaction. The term "Oxo reaction" is a general term used to describe the preparation of oxygenated organic compounds by the reaction of carbon monoxide and hydrogen with olefinic hydrocarbons in the presence of a carbonylation catalyst. The method is used particularly for the manufacture of various primary alcohols, more specifically octyl alcohols, by operations involving interaction of carbon monoxide, hydrogen, a hydrocarbon mixture containing substantial amounts of heptenes, and a cobalt carbonylation catalyst to form octyl aldehydes, and subsequent reduction

2

of these aldehydes by catalytic hydrogenation to a mixture relatively high in alcohols.

Primary alcohols of this general type are of great economic importance and interest because of their use as intermediates in the manufacture of plasticizers of the di-ester type. These alcohols have previously been supplied mainly by such comparatively costly procedures as aldol condensation of butyraldehydes, followed by dehydration, and hydrogenation of the resulting unsaturated octyl aldehyde. The Oxo reaction and subsequent hydrogenation have been found to comprise a highly economical and valuable method for manufacturing alcohols from cheap and readily available hydrocarbon material chiefly of petroleum origin.

In the carbonylation stage of the process, a large number of different types of reaction take place to form a variety of products. The primary reaction products will be aldehydes. These aldehydes themselves can undergo further reactions to yield other products. For instance, the aldehydes condense with each other to yield aldols. At least a part of the aldols undergoes dehydration to alpha-beta-unsaturated aldehydes. Some ketones are also formed under the reaction conditions. A part of the aldehydes formed in the reaction zone is hydrogenated to alcohols and the alcohols so formed react with aldehydes and ketones present to give mixtures of acetals, hemiacetals, and ketals. These compounds can undergo further reactions, including dehydration, to give ethers, particularly those of the unsaturated types. The alcohols can esterify the acids present to give esters. Hydrogenation of a part of the olefin starting feed stock, as well as some deoxygenation of oxygenated intermediates, gives some hydrocarbons in the final Oxo product. In addition, other more complex and less known reactions also occur between the various intermediates and products obtained thereby yielding a mixture of higher boiling impurities and contaminants of the oxygenated type.

In the hydrogenation stage, the mixtures of acids, saturated and unsaturated aldehydes, alcohols, ethers, aldol condensation products, glycols, acetals, ketals and esters are hydrogenated in the presence of a suitable catalyst to yield more saturated products containing a higher percentage of alcohols and non-olefinic compounds. Some of these impurities, especially the unsaturated ethers, acetals, ketals, aldols and esters are quite unstable toward heat and are sensitive generally to high temperature conditions. For instance, in general, the aldols, acetals, hemi-acetals and ketals have a great tendency to undergo

degradative decomposition reactions whenever the alcohol is subjected to a simple distillation regardless of whether the distillation be carried out at superatmospheric, atmospheric, or subatmospheric pressures provided the critical degradation temperature is reached. In many cases, thermally unstable esters are present and undergo both thermal and hydrolytic decompositions under ordinary distillation conditions.

A mechanism which fits the facts in a general fashion may be formulated in which it is assumed that decomposition reactions of various thermally and hydrolytically unstable materials proceed to an appreciable extent at the distillation temperature of the alcohol being purified, in this particular case, the isoctyl alcohol which has a boiling point of about 193° C. (380° F.) at atmospheric pressure. The decomposition reactions occurring always produce water, especially by aldol dehydration, and this water probably contributes further to decomposition reactions by its hydrolytic action, especially on esters, ketals, acetals, and unsaturated ethers. The more volatile of the decomposition products, including various saturated and unsaturated aldehydes, water, and alcohols (including both isoctyl and other alcohols of lower boiling point), go overhead with the alcohol product and contaminate the latter. Any aldehydes which are, in general, quite volatile, are distilled over with the alcohol fraction in this manner and can subsequently combine very readily with the distilled alcohol product, reforming acetals and hemi-acetals, which are likewise subject to a second decomposition when redistillation of the alcohol fraction is attempted. Furthermore, aldehyde and other decomposition products are objectionable because they lower overall product purity, and, due to instability, cause difficulties in the use of the alcohol. It is believed, however, that this is an oversimplified and incomplete picture of the overall situation.

It can readily be seen that it is difficult, if not impossible, to obtain relatively complete recovery of the Oxo alcohol by a distillation step and at the same time, to avoid contaminating the alcohol product by degradative and thermal decomposition of the higher boiling impurities present in the alcohol.

Perhaps the most important commercial use for these higher molecular weight alcohols, such as the C₈ isoctyl alcohols produced by the Oxo reaction, is in esterification reactions to form compounds of the diester type for use as plasticizers in resin and plastic compositions. Those of the phthalate and adipate type are widely manufactured. Even though an alcohol product of a synthetic source appears to be colorless, it frequently contains small amounts of impurities which form colored bodies during the subsequent acid-alcohol reaction. These colored materials are difficult to remove from the resulting high-boiling ester products and result in inferior esters which require additional and excessive purification prior to their use as plasticizers.

Since the alcohols are to be used principally in the preparation of plasticizer esters, the color and general purity qualities are best determined by a study of the ester produced from the alcohol. In typical alcohol esterification operations, a 20% molal excess of Oxo alcohol is used based on the phthalic anhydride used, that is, about 2.4 moles of alcohol per mole of phthalic anhydride. The esterification reaction is carried to substantial completion by esterification for a sufficient time. The unreacted alcohol is then

stripped off from the ester product preferably under reduced pressure and blended with fresh alcohol for returning to the esterification zone. Thus, undesirable color forming materials have 5 the opportunity to build up during the recycle stages to a point at which they must be purged from the system before continuing the recycling operation. This presents impurity problems when even small amounts of impurities consistently exist in the alcohol.

To obtain the data on comparative ester Hazen colors, esterification reactions were carried out during a period of 2 hours at the boiling point of the mixture. The crude esterification mixture 15 was then cooled and compared with Hazen color standards. A complete description of the standard Hazen ester color test is found in A. S. T. M. D-268-46.

This same type of problem of unstable impurities also exists in connection with other alcohols made by the Oxo reaction, and is particularly troublesome for the higher boiling alcohols of the range of C₄ to C₁₅ or higher. For example, the C₈ alcohols, prepared by the reaction of C₈ olefins such as diisobutylene with carbon monoxide and hydrogen may be purified in the same manner as that described herein for the purification of the C₈ Oxo alcohols.

It can thus be seen that it is of great desirability to obtain the alcohol products, particularly those of the type obtainable from synthetic processes of the Oxo process, as free of aldehydes, acetals and other chemically reactive and unstable substances as possible when the alcohols 30 are intended for use as esterification agents to make plasticizers.

A very superior procedure has been discovered by which the Oxo alcohols can be distilled and substantially completely recovered and, at the same time, the difficulty of contamination by cracked by-products of the heavy polymeric bottoms can be avoided.

This improved purification process can be used for purification of alcohols containing thermally 45 unstable high boiling impurities obtained from any source, and is especially applicable to treatment of alcohols having from 4 to 15 carbon atoms. It finds particular application in purification of alcohols obtained by the so-called Oxo reaction mentioned above and especially to alcohols of the C₈ and C₉ class, although the process can also be applied advantageously for other alcohols containing similar types of thermally unstable impurities, particularly alcohols obtained by hydrogenation of carbonyl compounds.

In the accompanying drawing, Figure 1 is a plot of the analytical distillation of a crude Oxo alcohol.

Figures 2 and 3 are diagrammatic representations of two different embodiments of our process.

A typical C₈ crude Oxo alcohol mixture such as can be employed as starting feed in this improved purification process has the following composition:

	Weight per cent
Alcohol as C ₈	65.0
Aldehyde as C ₈	1.8
Acetal as C ₂₄	3.7
Ester as C ₉	3.0
Unsaturates as C ₇	6.3
Acid as C ₈	0.1
Water	2.0
75 Saturates and unknowns	18.1

Analytical distillation of the crude C₈ Oxo alcohols from the hydrogenation step following carbonylation of a C₇ polymer olefin clearly shows that the impurities exhibit thermal sensitivity in that they appear to decompose at temperatures of about 260° C. (500° F.). Figure 1 shows a plot of data from such an analytical distillation. The vapor and pot temperatures have been plotted together with an indication of the temperature values at which sample cuts were removed for testing. The plot of the pot temperature indicates a sharp rise in temperature at about 260° C. (500° F.) showing cracking has begun when about 51% of the charge has passed overhead.

In Figure 1 in which the batch analytical distillation of a crude C₈ Oxo alcohol is plotted, the heavy ends region shows evidence of considerable undesirable cracking. While there does not appear to be any exact critical temperature for cracking, since the extent of decomposition is dependent on the time of high temperature exposure as well as on the temperature, it appears that if a "pot" or bottoms temperatures of 260° C. (500° F.) exists for an appreciable time interval, there is extensive decomposition of the heat sensitive bottoms and contamination of the alcohol removed as an overhead stream. The table below shows data obtained in tests carried out on the cuts removed from the analytical distillation.

TABLE

Cut.....	6	7	8	9	10	11	12	13	14
Ultraviolet Absorption at 2500 Å.....	2.000	1.475	0.242	0.191	0.230	0.210	0.316	0.955	1.800
Alcohol Hazen No.....	50	180	<25	<25	<25	<25	30	150	150
Phthalation Ester Hazen No..... (Pt-Co Scale).....	220	520	240	120	195	220	320	460	500

Since ester color is considered to be extremely critical and is perhaps the most important quality factor in determining the usefulness of the Oxo alcohols to prepare the ester plasticizers, the above data in the table are very important in that they clearly show that certain of distilled cuts of Oxo alcohol are clearly superior to other cuts for preparing such esters. Thus, the cuts numbered 8 to 11 are superior as to this very critical quality to cuts 12 to 14, the latter being obtained, as shown in the graph of Figure 1, after the pot temperature had risen to and above the critical decomposition point of 260° C. (500° F.), the temperature at which the higher boiling Oxo alcohol impurities start to undergo thermal cracking and degradation as is shown by the high ester Hazen number in the above table for these cuts.

In order to avoid the difficulties of either losing a substantial portion of the alcohol in the bottom by stopping the distillation below the temperature at which cracking takes place, or recovering the major portion of alcohol in an impure state contaminated by color forming impurities produced by the cracking of the bottoms, it has been found highly effective to add an additional agent to the alcohol undergoing distillation.

A liquid of boiling point about 20 to 100 degrees on the Fahrenheit scale above the boiling point of the alcohol is added to the distilling pot. This material enables the distillation of the alcohol to be completed, thereby recovering substantially all of the alcohol fed to the column and, at the same time, assists in keeping the

temperature low, such that cracking of bottoms impurities and subsequent alcohol contamination are virtually prevented.

For instance, in distilling a crude C₈ Oxo alcohol boiling in a range of 175-193° C. (350-380° F.), it is convenient to add a thermally stable, inert material of boiling range 205-260° C. (400-500° F.). This material can be a high boiling alcohol, as a C₈ Oxo alcohol, boiling about 205° C. (400° F.) if available. Hydrocarbon fractions of the proper boiling range are also conveniently useful. For example, an inert fraction boiling between 205-260° C. (400-500° F.) can be employed in conjunction with a C₈ alcohol. For other alcohols, the materials to be added are chosen with boiling points and ranges suitably adjusted. The hydrocarbon can be recovered and recycled to the distillation. Care should be exercised in choosing the inert fraction to avoid one which forms an azeotrope or constant boiling mixture with the alcohol being recovered.

It is also an additional feature that, rather than add an inert hydrocarbon material to the distillation, the olefinic feed to the Oxo reaction itself should be a mixture containing a portion of an olefin for which the corresponding alcohol derived by the Oxo reaction, will have a boiling point in the range required to prevent high bottoms temperature. This higher molecular weight alcohol can be recovered later and recycled or used otherwise.

In either case, the effect on the distillation is to have a bottoms fraction composed largely of the added alcohol or hydrocarbon, thus permitting maximum recovery of the desired Oxo alcohol. To this end the amount of the higher boiling material used is not critical but should be sufficient to effectively maintain lower temperatures in the fractionating tower bottoms. An amount of from 10% to 50% based on the total feed is adequate for temperature control. For economy purposes, the amount used should be that which is low enough to do the proper job effectively.

It is considered that the improvements obtained by the use of this higher boiling material may be achieved by applying this process in any type of operation wherein an Oxo alcohol or alcohol containing high boiling impurities sensitive to thermal decomposition is subjected to a distillation.

Two specific embodiments of this improved process are presented herewith although it is to be understood that the invention may be practiced in other ways which will be apparent to those skilled in the art.

Example 1

This example can best be understood by reading it in conjunction with Figure 2. About 90 parts by volume of a mixed olefin feed containing approximately 80% C₇ olefin and 20% C₈ olefin is fed by line 1 to an Oxo alcohol plant 2 wherein the olefins undergo carbonylation by catalytic reaction with carbon monoxide and hydrogen under suitable conditions of temperature and

pressure, to give aldehydes, followed by a catalytic hydrogenation of the aldehydes to a mixture of about 100 parts by volume of C_8 and C_9 Oxo alcohols together with higher boiling impurities such as ethers, esters, and acetals. About 100 parts by volume of these mixed alcohols are passed via line 3 to an intermediate point of topping tower 4. From overhead of tower 4 by line 5 a vapor stream is obtained which is liquefied in condenser 6 and obtained in line 7 as a recovered stream of about 20 parts by volume of unreacted olefinic feed. From the bottom of topping tower 4, the alcohols and higher boiling impurities are removed through line 11. A part of the alcohol stream in line 11 is recycled back to the tower by lines 8 and 10 and through external heater 9 to supply heat for the tower. About 80 parts by volume of the feed is eventually removed as mixed C_8 and C_9 alcohols and higher boiling impurities by line 11 and passed to an intermediate point of alcohol distillation tower 12. Overhead from distillation tower 12, there is removed a C_8 alcohol fraction by line 13. This alcohol is condensed in condenser 14 and a liquid stream removed by line 15. A part of this stream is recycled back to the distillation tower 12 by line 17 as reflux and a portion, about 48 parts by volume of the 80 parts of feed to tower 12, is recovered as finished C_8 Oxo alcohol of boiling point 175-193° C. (350-380° F.). This C_8 alcohol fraction is relatively free of color forming impurities because of the presence of the C_9 alcohol in the bottoms product. This C_8 fraction permits the temperature operation of distillation tower 12 to be kept lower. Thus, the bottoms temperature does not substantially exceed 260° C. (500° F.), and at the same time recovery of C_8 alcohol is substantially complete. From the lower part of the tower 12 by line 21 a stream of C_9 alcohol and bottoms is removed. A part of this stream is recycled by lines 18 and 20 through outside heater 19 to the tower 12 to supply heat. The remainder of the mixture is passed through line 21 to a C_9 alcohol recovery tower 22. Overhead from tower 22 there is removed a vapor stream of C_9 alcohol which is passed to a condensing and treating system 24 from which it emerges through line 25 as about 12 parts of finished C_9 alcohol of boiling range 193-210° C. (380-410° F.).

From the lower part of recovery tower 22 in which the bottoms temperature is 260° C. (500° F.) or higher, there is removed via line 26, a bottoms product, a major portion of which boils over 210° C. (410° F.). A part of this higher boiling material consisting of acetals, ethers, and esters, is recycled by lines 27 and 29, through external heater 28, back to tower 22 and about 20 parts by volume is removed as bottoms by line 30.

Example 2

As an alternate procedure in which a suitably boiling hydrocarbon fraction is added to the alcohol, Example 2 is best understood by reference to Figure 3.

About 90 parts by volume of a relatively pure C_7 olefin is fed by line 50 to an Oxo alcohol plane 51 wherein the olefin undergoes carbonylation by a catalytic reaction with carbon monoxide and hydrogen under suitable conditions of temperature and pressure to give a C_8 aldehyde, followed by a catalytic hydrogenation of the aldehyde to about 100 parts by volume of an isoctyl alcohol together with higher boiling

impurities such as ethers, esters, and acetals. About 100 parts by volume of this C_8 alcohol is passed by line 52 into an intermediate point of topping tower 53. From overhead of tower 53 by line 54 a vapor stream is obtained which is liquefied in condenser 55 and obtained in line 56 as a recovered stream of about 20 parts of unreacted olefinic feed. From the bottom of topping tower 53 the alcohol and higher boiling impurities are removed through line 57. A part of this stream is recycled via lines 58 and 60 through external heater 59 back to tower 53 to supply heat thereto. A major portion consisting of about 80 parts by volume of the impure alcohol stream is taken by line 61 to an intermediate point of alcohol distillation tower 62. There is introduced into line 61 and subsequently into the tower 62 at least 10 parts by volume of a stable hydrocarbon cut boiling from 205-260° C. (400-500° F.). The hydrocarbon cut may be from a recycle stream or it may be fresh make-up feed. Overhead from distillation tower 62, there is removed a C_8 alcohol vapor stream by line 63. This vapor stream is condensed by condenser 64 and a liquid alcohol stream is collected in line 66 a portion of which is refluxed back to tower 62 by line 67. About 60 parts by volume of finished C_8 alcohol of boiling range 175-193° C. (350-380° F.), from the 80 parts of impure alcohol, are recovered from tower 62. This C_8 alcohol fraction is relatively free of color forming impurities because of the presence of the stable hydrocarbon fraction in the tower bottoms. This hydrocarbon fraction permits the temperature operation of distillation tower 62 to be kept lower. Thus, the bottoms temperatures does not substantially exceed 232° C. (450° F.) or, at a maximum 260° C. (500° F.), and, at the same time, recovery of the C_8 alcohol is substantially complete. From the lower part of the tower 62 by line 68 a stream of hydrocarbon and high boiling bottoms is removed. A part of this stream is recycled by lines 69 and 71 through outside heater 70 to the tower 62 to supply heat. The remainder of the high boiling mixture is passed through line 68 to a hydrocarbon recovery tower 72. Overhead from tower 72 there is removed a vapor stream of the hydrocarbon cut which is passed to a condensing and treating system 74 from which the recovered hydrocarbon cut is passed by lines 75, 82, and 61 back to alcohol distillation tower 62. Through hydrocarbon make-up line 81 additional hydrocarbon is added if necessary to supply the proper amount of hydrocarbon cut to tower 62 to keep the bottoms temperature below 232-260° C. (450-500° F.).

From the lower part of hydrocarbon recovery tower 72 in which the bottoms temperature is 500° F. or higher, there is removed via line 76 a high boiling bottoms product, the major portion being acetals, ethers, and esters. A part of this is recycled by lines 77 and 79 through heater 78 back to tower 72. About 20 parts are removed as bottoms by line 80.

What is claimed is:

1. An improved distillation process for the purification of an impure primary alcohol produced by the Oxo process and containing from four to fifteen carbon atoms and which contains high boiling unstable impurities including acetals, esters, hemi-acetals and ethers which tend to decompose upon heating, which comprises subjecting the alcohol to a vaporization in a vaporization zone in the presence of an inert,

thermally stable liquid, which does not azeotrope with and has a boiling point of from 20 to 100 Fahrenheit degrees above that of the alcohol, the boiling point of said inert liquid being intermediate to the alcohol being purified and the high boiling impurities, maintaining the liquid temperature in the vaporization zone at all times below the critical decomposition temperature of the high boiling unstable impurities, said critical decomposition temperature being higher than normal boiling point of the alcohol being purified, and recovering as a vapor stream substantially all of the alcohol uncontaminated by volatile impurities.

2. A process such as that described in claim 1 in which the inert, thermally stable liquid is present in an amount of from 10% to 50% based on the total liquid including the alcohol.

3. An improved continuous distillation process for the purification of a primary alcohol having from 4 to 15 carbon atoms containing high boiling unstable impurities including acetals, esters, hemi-acetals and ethers and obtained by the catalytic reaction of olefins with carbon monoxide and hydrogen and subsequent hydrogenation of the aldehydes resulting therefrom, which comprises introducing said alcohol and impurities together with an inert, thermally stable alcohol higher boiling than the alcohol being purified, said higher boiling alcohol being one which does not azeotrope with and has a boiling point of from 20 to 100 Fahrenheit degrees above that of the alcohol being purified into a distillation zone, the boiling point of said inert alcohol being intermediate to the alcohol being purified and the high boiling impurities, continuously maintaining the liquid within said zone below the critical decomposition temperature of the high boiling unstable impurities said critical decomposition temperature being higher than normal boiling point of the alcohol being purified, recovering as a vapor stream substantially all of the alcohol being purified uncontaminated by volatile impurities, and recovering the inert, thermally stable higher boiling alcohol as a separate fraction.

4. A process such as that described in claim 3 in which the inert thermally stable higher boiling alcohol is present in an amount of from 10% to 50% based on the total liquid including the alcohol being purified.

5. An improved continuous distillation process for the purification of a primary C₈ iso-octyl alcohol of normal boiling range 350 to 380° F., obtained by catalytic reaction of a C₇ olefin stream with carbon monoxide and hydrogen and subsequent hydrogenation of the C₈ aldehydes obtained therefrom, and containing high boiling thermally unstable impurities including acetals, esters, hemi-acetals and ethers, which comprises introducing said alcohol and impurities, together with an inert, thermally stable alcohol higher boiling than the alcohol being purified, said higher boiling alcohol being one which does not azeotrope with the C₈ iso-octyl alcohol and has

a boiling point of from 400 to 500° F., into a distillation zone, the boiling point of said inert alcohol being intermediate to the alcohol being purified and the high boiling impurities, continuously maintaining the liquid within said zone below 500° F., removing overhead as a vapor stream from said distillation zone substantially all the C₈ iso-octyl alcohol uncontaminated by volatile impurities, and recovering the inert, thermally stable higher boiling alcohol as a separate fraction.

6. A process as described in claim 5 in which the inert thermally stable liquid is a hydrocarbon fraction of 400° to 500° F., boiling range and in which the hydrocarbon is separated from the high boiling bottoms of the distillation zone and recycled back to the distillation zone.

7. An improved continuous distillation process for the purification of an impure primary C₈ iso-octyl alcohol of boiling range 350°-380° F. obtained by the catalytic reaction of olefins with carbon monoxide and hydrogen and subsequent hydrogenation of the aldehydes resulting therefrom, which comprises reacting a mixed olefin stream containing substantial proportions of C₇ and C₈ olefins with carbon monoxide and hydrogen, subsequently hydrogenating the C₈ and C₉ aldehydes obtained therefrom, introducing the resulting C₈ and C₉ alcohol mixture together with high boiling, thermally unstable impurities including acetals, esters, hemi-acetals and ethers into a distillation zone, the boiling point of said C₉ alcohol being intermediate to the C₈ alcohol and the high boiling impurities, maintaining continuous reflux within said distillation zone, maintaining the temperature within said distillation zone at all times below 500° F., removing overhead from said distillation zone as a vapor stream substantially all the C₈ alcohol uncontaminated by volatile impurities, removing as liquid bottoms from said distillation zone a mixture of C₉ alcohol and high-boiling impurities including acetals, esters, hemi-acetals and ethers, introducing said bottoms mixture into a second distillation zone, removing overhead from said second distillation zone substantially all the C₉ alcohol, and removing from the lower portion of said second distillation zone the high-boiling, thermally unstable impurities as a liquid bottoms product.
